SNAP-ON HOLDER

Paul D. Phillips, Des Plaines, Ill., assignor to
 Benjamin Electric Mfg. Company, Des Plaines,
 Ill., a corporation of Illinois

Application November 7, 1932. Serial No. 641,504

5 Claims. (Cl. 240—128)

My invention relates to shade securing means. In certain types of reflectors it has heretofore been the practice to provide each reflector with means permanently secured thereto for attaching the reflector in position with respect to a lamp socket. As there are various types of lamp sockets, different forms of attaching means had to be provided for these reflectors in order to adapt them for the different types of sockets. As the attaching means were permanently secured to the reflectors, this necessitated that the distributor or dealer carry a line of reflectors for each type of socket.

One of the objects of my invention is to provide a reflector supporting attachment which can be readily attached and detached with respect to the reflector so that by having a suitable supply of various types of these attachments on hand the dealer or distributor can fit up a single line of reflectors for use with any of the various types of sockets, thus enabling him to carry but a single line of reflectors, where heretofore it had been necessary for him to carry a number of lines, one for each type of socket.

A further object is to provide such a construction in which a substantial portion of the reflector supporting attachment is located inside the neck of the reflector.

A still further object is to provide such a construction which will be durable and efficient in use and inexpensive to manufacture.

Further objects will appear from the description and the appended claims.

In the drawings in which three forms of the invention are shown:

Figure 1 is a fragmentary side elevational view showing a reflector secured in position with respect to a porcelain socket;

Fig. 2 is a plan view of the attachment;

Fig. 3 is a section on line 3—3 of Fig. 2;

Fig. 4 is a perspective of one of the securing springs;

Fig. 5 is a side elevational view showing another form of attachment;

Fig. 6 is a plan view of the attachment of Fig. 5;

Fig. 7 is a section on line 7—7 of Fig. 6;

Fig. 8 is a side elevational view of another form of attachment;

Fig. 9 is an axial section through the attachment of Fig. 8; and

Fig. 10 is a section on line 10—10 of Fig. 9.

Referring to the drawings in detail and first to Figs. 1 to 4, inclusive, the construction shown therein comprises a porcelain socket 1 having an

outwardly extending annular flange 2 at its lower end, a reflector 3 having an inwardly extending annular flange 4 at its upper end and a reflector supporting member 5 having a snap connection with the inwardly extending flange 4 of the reflector and having a clamping connection with the porcelain socket.

The snap connection comprises a pair of duplex leaf spring members 7 and 8 riveted at 9 to the inside of the annular collar 10 which can be inserted down through the opening in the annular flange 4 of the reflector. This annular collar 10 is provided with four apertures 11, one for each end of each of the duplex springs 5, thus enabling these latch-like ends to extend through the openings into latching engagement with the underside of the reflector flange 4. These latching ends are beveled off as indicated in Figs. 1, 3, and 4, to facilitate their entry into the opening in the reflector flange, the slope being such that the latched ends are forced inwardly as the collar is inserted into the flange opening, the latch members snapping out as soon as their upper edges have passed underneath the reflector flange.

The distance to which the collar 10 can be inserted into the flange opening is limited by the engagement of the downwardly bumped portions 12 of the outwardly extending flange 13 at the upper end of the collar which engage the upper surface of the inwardly extending flange of the reflector. These downwardly bumped projections 12 provide a slightly yielding engagement with the flange of the reflector, the flange being engaged on its lower side by the four spring latch members 5 and being engaged on the upper surface by the downwardly bumped projections 12 of the collar flange.

The clamp for securing the attachment to the socket comprises a pair of clamping members 14 riveted to the upwardly projecting ears 15 on the collar member 10 and having straps 16 punched inwardly for engagement above the annular supporting flange 2 on the socket. A pair of clamping screws 17 are provided for drawing the ends of the clamping members toward each other to bring the straps firmly into engagement with the sides of the socket. In order to hold the attachment in proper relation with respect to the reflector and prevent relative rotation therebetween, portions 18 of the outwardly extending flange are cut and struck downwardly so as to fit in suitably positioned notches 19 formed in the inwardly extending flange of the reflector.

With this construction, it will be seen that the

reflector supporting attachment can be readily attached to the reflector so that the attachments and reflectors can be shipped unassembled to the distributors and dealers who can then fit up the 5 reflectors as required with the desired type of socket attaching member.

Figs. 5, 6, and 7 show a reflector attachment for another type of socket in which portions of the socket of the interior construction are held 10 up by means of a threaded supporting ring 14a screwed inside of the threaded skirt portion 1a of the socket casing. In this form, the reflector supporting collar 10 is formed as an integral part of the screw ring 14a which serves to support the 15 socket interior. The collar and spring latching construction is precisely the same as that shown in Figs. 1 to 4, inclusive. The screw ring 14a is provided with an inwardly extending flange 20 at its upper end on which rests the shoulder of the 20 socket interior.

The construction shown in Figs. 8, 9, and 10 provides for connection of the shade with a 25 socket of the type having an exterior screw thread 1b on the lower part of the casing for engagement with a corresponding threaded portion 14b on the reflector supporting attachment. In this form also the collar portion and spring latch 30 construction may be identical with that of Figs. 1 to 4, inclusive, the collar being formed as an integral part of the sheet metal from which the threaded connector is formed.

Further modifications will be apparent to those skilled in the art and it is desired, therefore, that the invention be limited only by the prior 35 art and the scope of the appended claims.

Having thus described my invention, what I claim and desire to secure by Letters Patent is:

1. The combination with a shade or reflector construction having an inwardly extending annular flange at its upper portion, of a shade holder 40 construction comprising a collar insertable into the opening of the flange, spring latching means carried by the collar for snapping over the flange, and means for securing said collar in position 45 with respect to a socket, said collar having an opening therein and said spring latching member lying partly within said collar and having a portion extending through said collar opening for engaging underneath said flange.

50 2. The combination with a shade or reflector

construction having an inwardly extending annular flange at its upper portion, of a shade holder construction comprising a collar insertable into the opening of the flange, spring latching means carried by the collar for snapping over the flange, and means for securing said collar in position with respect to a socket, said spring latching member comprising a leaf spring extending circumferentially of the collar. 80

3. The combination with a shade or reflector construction having an inwardly extending annular flange at its upper portion, of a shade holder construction comprising a collar insertable into the opening of the flange, spring latching means carried by the collar for snapping over the flange, and means for securing said collar in position with respect to a socket, said spring latching member comprising a leaf spring extending circumferentially of the collar, said collar having an opening therein and said spring latching member lying partly within said collar and having a portion extending through said collar opening for 85 engaging underneath said flange. 90

4. The combination with a shade or reflector construction having an inwardly extending annular flange at its upper portion, of a shade holder construction comprising a collar insertable into the opening of the flange, spring latching means carried by the collar for snapping over the flange, and means for securing said collar in position with respect to a socket, said collar being 100 apertured and said spring latching means comprising a leaf spring member secured intermediate its length to the collar and extending circumferentially of the collar, and having its ends projecting through the collar for engaging underneath the flange. 105

5. The combination with a shade or reflector construction having an inwardly extending annular flange at its upper portion, of a shade holder 110 construction comprising a collar insertable into the opening of the flange, spring latching means carried by the collar for snapping over the flange, and means for securing said collar in position with respect to a socket, said spring latching means comprising a leaf spring member secured intermediate its length to the collar and extending circumferentially of the collar and having its ends 115 projecting through the collar for engaging underneath the flange. 120
